UNITED STATES PATENT OFFICE.

JOHN JAMES MARRS, OF HARRISON, ARKANSAS.

VENDING-MACHINE.

1,057,971.

Specification of Letters Patent.

Patented Apr. 1, 1913.

Application filed December 2, 1909. Serial No. 531,002.

To all whom it may concern:

Be it known that I, JOHN JAMES MARRS, a citizen of the United States, and a resident of Harrison, in the county of Boone and State of Arkansas, have invented a new and Improved Vending-Machine, of which the following is a full, clear, and exact description.

My invention relates to vending machines and it has for its object to provide means which, when freed by a coin, are adapted to operate to discharge a newspaper or other periodical from within the casing.

Another object of the invention is to provide means which may be readily adjusted to regulate the tension of the spring connected with the lever, so that one, two, three or more coins will be required to operate it.

Another object is to provide slots in the coin chute through which slugs and small coins may fall before they reach the lever, plugs being also provided to fill the slots when desired.

A further object of the invention is to provide a slide with a flange, which is adapted to engage the side of a newspaper in the machine to push its end through the discharge slot, the slide having a recess which is normally engaged by the arm pivoted to the lever.

Still another object of the invention is to provide a rack sliding in a groove in the casing, there being means adapted to press the rack with newspapers, so that one of them is at all times in a position to be projected through the discharge slot by the flange.

Another object of the invention is to provide means for drawing back the rack to permit of the insertion of newspapers or other periodicals.

Still other objects of the invention will appear in the following complete description.

In this specification I will describe the preferred form of my invention, it being understood that the scope of the invention is defined in the appended claims.

Reference is to be had to the accompanying drawings forming a part of this specification, in which similar characters of reference indicate corresponding parts in all the views, in which—

Figure 1 is a perspective view of the machine; Fig. 2 is a sectional view showing the coin chute and the mechanism immedi-

ately connected therewith; Fig. 3 is a side sectional elevation of the invention; Fig. 4 is a view similar to that shown in Fig. 2, with the bell crank lever connected with the operating lever held in another position; Fig. 5 is a plan view of the machine with the cover removed, a portion of the side of the casing being shown in section to show the door closing the discharge slot; Fig. 6 is a sectional plan view of the front of the box, showing the relationship of the arm pivoted to the operating lever with the slide; Fig. 7 is a view showing the drum which is connected with the rack; and Fig. 8 is a view showing one of the plugs adapted to close an opening in the coin chute.

By referring to the drawings it will be seen that there is a casing 1, in which is a coin slot 2 which communicates with a coin chute 3, the coin chute being inclined downwardly from the coin slot 2 for a distance, in which portion of the coin chute there is an opening 4 in its bottom, the coin chute 3 then being inclined a greater degree toward a cup 5 on an operating lever 6. The bottom of the coin chute 3 is located above the cup 5. A plug 7 is provided, having a head 8 and a shank 9, this plug 7 being adapted to close the opening 4 in the bottom of the coin chute 3, the head forming a continuation of the bottom of the coin chute 3 and the shank 9 projecting through the opening 4. There is also an opening 10 in the coin chute 3, immediately beyond a point 11, which forms the apex at the bottom of the coin chute 3, which, as has been stated, is angular. The operating lever 6 is pivoted at 12 to the side of the casing 1.

A bell crank lever 13 is pivoted to the casing 1, one arm of the bell crank lever 13 being connected with the other arm of the operating lever 6 by a spring 14. A plate 15, with orifices 16, is secured to the casing and a pin 17 is provided, which is adapted to be disposed in any one of the orifices 16, and with which the arm of the bell crank lever 13 is adapted to contact to limit its movement. It will therefore be seen that by changing the position of the bell crank lever 13 and by holding it in its new position with the pin 17 inserted in one of the orifices 16, the tension of the spring 14 may be regulated.

Below the openings 4 and 10 in the coin chute 3, is a chute 18 which leads to a slot 19 in the casing. The opening 4 in the coin

chute 3 is provided to receive pennies when the machine is arranged to sell newspapers or other periodicals, the price of which is five cents. When the machine is so adjusted, any penny which may be inserted through the coin slot 2 will fall through the opening 4 into the coin chute 18 and through the coin slot 19 to a position without the casing. The opening 10 in the coin chute 3 is provided to permit slugs to fall therethrough which may be introduced through the coin slot 2, for whether the machine be adjusted to sell newspapers, the price of which is one cent, or whether it is arranged to vend newspapers for five cents each, the coins which the purchaser will introduce through the coin slot 2 will pass over this opening 10, although slugs because of their size and weight, will fall therethrough into the chute 18.

A stop 20 is secured to the casing 1 near the inner terminal of the coin chute 3, to prevent the coins from leaving the coin chute before striking the cup 5. Connected with the operating lever 6 there is an arm 21 which is pivoted on the pin 12 to which the operating lever 6 is also pivoted, the operating lever 6 having a flange 22 disposed in the arm 21 to lift it when a coin falls in the cup 5, secured to the operating lever.

In the front of the machine there is a groove 23, in which a slide 24 is adapted to travel, there being a slot 25 which communicates with the groove 23, and a knob 26 projecting through the slot 25, the knob 26 being secured to the slide 24. The slide 24 has a recess 27 which extends through its upper surface, the arm 21 being normally disposed in the said recess. The front of the casing 1 has a recess 28 sufficiently large to permit of the movement of the arm 21 therein. The end of the slide 24 at 29 is curved so that when the slide has been released and is then drawn back by a spring 30, the curved portion 29 of the slide 24 will lift the arm 21 so that it may fall in the recess 27. To the slide 24 is secured a flange or hand 31. Running from the front to the rear of the machine, at its base, there is a guideway 32, in which is disposed a slide 33, a rack 34 being mounted on this slide 33, the newspapers or other periodicals 35 being moved toward the front of the machine by this rack 34. At the side of the front of the machine and opposite the flange or hand 31, there is a discharge slot 36, at one side of which is pivoted a door 37, there being an arm 38 which is secured at right angles to the door, this arm 38 being connected to the side of the casing by means of a spring 39. This means is provided to hold the door 37 yieldingly closed, said door being adapted to move outwardly by the pressure of a newspaper or other periodical, the spring 39 tending to close the door after the paper has been removed, a shoulder 40

in the casing limiting the inward movement of the door.

At the rear of the machine is journaled in standards 41, a shaft 42 on which is mounted a drum 43, there being also a spring 44 mounted on the shaft 42, the spring 44 being adapted to rotate the shaft in one direction. At the front of the machine and in the guideway 32 is journaled a roller 45. A belt 46 is provided, which is disposed around the drum 43, one end of the belt 46 being disposed beneath the slide 33 around the roller 45 and then to the slide 33 where it is secured. The other end of the belt 46, after it is disposed around the drum 43, is also secured to the slide 33. The spring 44 is so mounted that it tends to draw rearwardly the lower portion of the belt 46, thereby moving the slide 33 yieldingly forward with the newspapers or other periodicals 35 disposed at the front of the casing. There is also secured to the drum 43 a belt 47, the belt being wound around the said drum and then being led through eyes 48. The belt serves to rotate the drum against the pressure of the spring to move the slide 33 toward the rear of the machine, which will enable the operator to dispose the newspapers between the front of the machine and the rack 34.

In using the invention, after the newspapers have been disposed in the machine, the party desiring to purchase a newspaper introduces a coin in the coin slot 2, the coin rolling down the coin chute 3 and falling into the cup 5, which operates the lever 6, the flange 22 on the lever 6 lifting upwardly the arm 21 out of the recess 27 in the slide 24. The party is then able to move the slide from right to left by means of the knob 26 and when this is done, the flange or hand 31 engages the newspaper in the front of the pile of newspapers and pushes it against the door 37 and a short way through the discharge slot 36. The party is then able to withdraw the newspaper the rest of the way, and the transaction is completed.

At all times the spring 44 in connection with the belt 46, holds the rack 34 yieldingly against the newspapers or periodicals 35, so that when any party desires to operate the machine, he may feel certain that a newspaper is in position to be engaged by the flange or hand 31. In the front of the casing 1, there is a glass window 49, which will permit the party to look through to see if the receptacle is empty and if he sees a newspaper in the receptacle, he may rest assured that it will be discharged when the machine is operated.

When the machine is used to sell newspapers, the price of which is one cent each, the opening 4 in the coin slot 3 is fitted with the plug 7, for when this plug is used, a one-cent piece will pass over the plug, down the 130

- chute and will not fall through the opening 4. When the plug 7 is not in use, a one-cent piece will fall through the opening 4 into the chute 18, although a five-cent piece will 5 pass down the chute, over the opening 4. It will therefore be seen that the machine may be used to sell papers which cost one cent, as well as those which cost five cents each.
- 10 When it is desired to sell newspapers costing two cents, the tension of the spring 14 is adjusted by moving rearwardly the upper arm of the bell crank lever 13 and securing it in place by the pin 17 disposed in one of the orifices 16. When this is done, it will be necessary for two one-cent pieces to fall into the cup 5 before the operating lever 16 is caused to descend by the weight of the coins. The machine may therefore be used 15 to sell newspapers whether they cost one, two or five cents.
- Having thus described my invention, I claim as new and desire to secure by Letters Patent:
- 20 1. In a vending machine, a lever adapted to be operated by a coin, a second lever, a spring connecting an arm of the second-mentioned lever with an arm of the first-mentioned lever, adapted for holding the first-mentioned lever yieldingly in a predetermined position, and means adapted for limiting the movement of the second-mentioned lever in the direction of the pull of the spring.
- 25 2. In a vending machine, a lever adapted to be operated by a coin, a second lever, a spring connecting an arm of the first-mentioned lever with an arm of the second-mentioned lever adapted for holding the first-mentioned lever in a predetermined position, a member having a plurality of orifices, and a pin adapted to be disposed in any one of the orifices and to engage the arm of the second-mentioned lever.
- 30 3. In a vending machine, a coin chute having an opening in its bottom, a shank having a head, the shank being adapted to be inserted in the opening so that the head will close it, a lever adapted to be operated by a coin as it falls from the coin chute, a second lever, a spring connecting an arm of the second-mentioned lever with an arm of the first-mentioned lever, adapted for holding the first-mentioned lever yieldingly in a predetermined position, and means adapted for limiting the movement of the second-mentioned lever in the direction of the pull of the spring.
- 35 4. In a vending machine, a lever adapted to be operated by a coin, a second lever, a spring connecting an arm of the second-mentioned lever with an arm of the first-mentioned lever, adapted for holding the first-mentioned lever in a predetermined position, a member having a plurality of orifices, and a pin adapted to be disposed in any one of the orifices and to engage the arm of the second-mentioned lever.
- 40 5. In a vending machine, a casing having a discharge slot, a lever adapted to be operated by a coin, a spring adapted for holding the lever yieldingly in a predetermined position, a slide having a recess, an arm pivotally connected to the lever adapted to be disposed in the recess, a flange secured to the lever adapted to contact with the arm, a flange secured to the slide, a second slide, a rack secured to the second-mentioned slide, and means adapted for holding the second-mentioned slide yieldingly in a predetermined position.
- 45 6. In a vending machine, a lever adapted to be operated by a coin, a spring adapted for holding the lever yieldingly in a predetermined position, a slide having a recess, an arm pivotally connected to the lever adapted to be disposed in the recess, a flange secured to the lever adapted to contact with the arm, a flange secured to the slide, a second slide, a rack secured to the second-mentioned slide, and means adapted for holding the second-mentioned slide yieldingly in a predetermined position.
- 50 7. In a vending machine, a casing having a discharge slot, a lever adapted to be operated by a coin, a spring adapted for holding the lever yieldingly in a predetermined position, a slide having a recess, an arm pivotally connected to the lever adapted to be disposed in the recess, a flange secured to the lever adapted to engage the arm, a flange secured to the slide, a second slide, a rack secured to the second-mentioned slide, means adapted for holding the second-mentioned slide yieldingly in a predetermined position, a door adapted to close the discharge slot in the casing, and means adapted for holding the door yieldingly closed.
- 55 In testimony whereof I have signed my name to this specification in the presence of two subscribing witnesses.
- JOHN JAMES MARRS.
- Witnesses:
- L. M. WHITESIDE,
C. E. WILSON.
